UNITED STATES PATENT OFFICE

RAYMOND L. HAWKINS, OF DETROIT, MICHIGAN, ASSIGNOR TO LONG MANUFACTURING COMPANY, OF DETROIT, MICHIGAN, A CORPORATION OF MICHIGAN

RADIATOR

Application filed October 24, 1927. Serial No. 228,419.

This invention relates to radiators and more especially to improvements in radiators finding particular utility wherever heat exchange apparatus is required.

5 The invention has as one of its objects to provide an improved radiator construction designed to permit the ready expansion and contraction of the radiator without distortion thereof or other objectionable reaction. 10 To this end the invention contemplates the provision of spaced headers rigidly connected by tubes extending therebetween and side plates also extending between the headers but loosely or slidably connected therewith so as 15 to permit the expansion and contraction of the headers and tubes as a unit independent of the side plates.

The invention also contemplates a structure which may be manufactured economically and assembled with facility and to this end contemplates a header comprising a substantial box-like shell or casing open at one end thereof. One of the walls of the header, preferably the side opposite the open side 25 thereof, is formed with tube receiving apertures into which the adjacent ends of the tubes extend. With a header of an open shell-like construction the tubes may be soldered in place from the inside of the header whereupon the header is closed by means of a cover resting on a peripheral shoulder adjacent the open side of the header.

The several objects, advantages and novel details of construction of this invention will 35 be made more apparent as this description proceeds especially when considered in connection with the accompanying drawings wherein:

Figure 1 is a vertical sectional view 40 through a radiator constructed in accordance with this invention.

Figure 2 is a horizontal section taken substantially on the plane indicated by line 2—2 in Figure 1, and

45 Figure 3 is a fragmentary perspective view. Referring now more particularly to the drawings wherein like reference characters indicate like parts, it will be noted that the radiator consists of spaced headers 10 each of 50 which comprises a substantially box-like

shell or casing open at one side thereof. The wall 11 of each header is formed with a plurality of tube receiving apertures 12 with which the tubes 13 of the radiator engage. The reference character 14 indicates the usual 55 fin plates associated with the tubes 13.

The side wall 15 of each header is formed with a peripherally inwardly extending shoulder 16 arranged adjacent the open side of the header with which a plate-like cover member 17 is adapted to engage. This cover member 17 may obviously be secured in place in any desired manner but is preferably brazed or welded thereto around its periphery as indicated at 18. For closing the sides 60 of the radiator and for the additional purposes of imparting thereto an attractive appearance I provide side plates 19, each of which has its longitudinal edges bent to form 65 return-bent portions 20. These return bent 70 portions provide grooves or recesses engageable with oppositely extending projections or ribs 21 formed on each header 10. Thus the side plates 19 may be slidably connected to the headers 10 to permit a relative sliding 75 movement between the parts while preventing lateral disengagement of the side plates.

In assembling a radiator constructed in accordance with this invention the tubes 13 may be introduced into the tube apertures 12 80 and soldered in place from the inside thereof, the cover plate 17 being, not yet in place. With the tubes 13 projecting upwardly from the lower header as viewed in Figure 1, the side plates 19 may then be slid into engagement with the ribs 21 formed on the lower header 10. The upper header 10 is then placed in engagement with the upper ends of the tubes 13 and slidably engaged with the upper ends of side plates 19. The ends of the tubes 13 may be soldered to the upper header 10 85 from the inside whereupon cover 17 is secured in place in the manner hereinbefore referred to.

In consequence of this construction the expansion and contraction of the tubes 13 and the resulting movement of the headers is permitted without interference from the side plates 19, a relative sliding movement between the headers and side plates taking place 90 95

under these conditions. Thus the headers are not held rigidly spaced by the side plates but are permitted to move toward and away from one another in consequence of the expansion and contraction of the tubes so that the radiator does not become distorted and the joints between the tubes and headers are maintained intact.

Obviously other means may be employed for connecting the side plates to the headers to permit a relative sliding movement therebetween although the herein described construction has proven to be economical, efficient and otherwise satisfactory. It will likewise be apparent that the expansion and contraction of the headers and tubes as a unit may be permitted even with the side plates permanently attached to the headers at one end thereof. Thus reservation is made to make such changes, modifications and arrangements of the parts as may be deemed necessary or expedient and as may come within the purview of the accompanying claims.

What I claim as my invention is:-

- 25 1. In a radiator, spaced headers, a side plate and projections and recesses carried respectively by said headers and plate for slidably securing said plate to said headers.
- 30 2. In a radiator, spaced headers, a side plate, projections formed on said headers, the edges of said side plate being bent providing recesses for slidable engagement with said projections.
- 35 3. In a radiator, spaced headers, laterally extending ribs formed on said headers, side plates, the longitudinal edges of said plates being return-bent forming recesses engageable with said ribs for slidably securing said side plates to said headers.
- 40 4. In a radiator construction, spaced headers, projections on said headers, and a plate-like member extending between said headers, said plate like member having portions slidably embracing the said projections on said headers.
- 45 5. In a radiator, a header member, a side plate member, and a projection formed on one of said members engageable in a recess formed in the other of said members for slidably securing said members together whereby said header is movable relative to said side plate.

In testimony whereof I affix my signature.
RAYMOND L. HAWKINS.
